DESIGN FOR A FIRE-PLACE.

Design No. 13,306, dated September 19, 1882.

UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A FIRE-PLACE.

SPECIFICATION forming part of Design No. 13,306, dated September 19, 1882.

Application filed August 11, 1882. Term of patent 7 years.

To all whom it may concern:

Be it known that I, WILLIAM TWEEDDALE, of Brooklyn, in the county of Kings and State of New York, have invented a Design for Fire-Places, of which the following is a specification.

This design relates to the fender, frame, and andirons composing the ornamental fire-place, the parts being designed to produce as a whole a certain artistic effect.

The main features of this design relate to the artistic effect produced by cross-bars and circles.

The fender portion is composed of the main longitudinal bars *a* and *b* and base *c*, with the main vertical bars *d*. These bars divide the fender up into sections. Between the bars *a* *b* *d* there are shorter intersecting bars, with center leaflet ornaments, *e*, in open-work, as shown, and between the bars *b* and *c* there is a range of circular ornaments *f* between the vertical bars. Above the bar *a*, and in line with the vertical bars *d*, there are globular ornaments *g*, and at the angles are columns *h*, with conical head-pieces *k* and pyramidal bases *n*, as shown.

The andirons are made with circular ornaments *l*, with scalloped edges and leaflet surface

ornaments, as shown, and with half-circle ornaments *m*—one at each side of the stem. 30

The fire-place frame is ornamented to correspond in general appearance with the fender and andirons, the surface being grooved to give it the appearance of bars, as at *u*, and having round ornaments *p*, with flowers and leaflets within, as shown. The upper angles are squares, with lines and circles, as shown at *r*, and the lower part of the sides of the frame are ornamented with horizontal bars *s*, angular bars *t*, and circular and leaflet ornaments, 40 as shown.

I claim as my invention—

1. The design of the fender, consisting of the bars, circles, and leaflet ornaments, as shown. 45
2. The design of the fire-place frame, consisting of the bars, circles, and leaflet and surface ornaments, as shown.

3. The design of the andirons, consisting of the circular heads, leaflet surface ornaments, and half-circular side ornaments, as shown. 50

Signed by me this 7th day of August, A. D. 1882.

WILLIAM TWEEDDALE.
